UNITED STATES PATENT OFFICE.

WILLIAM G. LAMB, OF WATERLOO, IOWA, ASSIGNOR TO A. I. WOODRING COMPANY, OF WATERLOO, IOWA.

REMOVABLE TROLLEY SHOE.

1,402,076.

Specification of Letters Patent. Patented Jan. 3, 1922.

Application filed May 9, 1921. Serial No. 467,981.

To all whom it may concern:

Be it known that I, WILLIAM G. LAMB, a citizen of the United States of America, and a resident of Waterloo, Blackhawk County, Iowa, have invented certain new and useful Improvements in Removable Trolley Shoes, of which the following is a specification.

This invention relates to improvements in removable shoes for trolley-wheels, and the object of the improvement is to provide a shoe for sliding electrical contact with a trolley-wire secured removably upon the trolley-wheel whereby either the sliding shoe or the trolley-wheel may be employed as desired. Particularly, an object of this combination is to permit a sliding shoe contact with a trolley wire at times when the vehicle on which it is mounted is travelling between stations, and a rolling contact when the vehicle, whether locomotive or car, is being used for switching purposes.

A sliding contact gives a superior result when the vehicle is travelling because the current is collected with less loss, less noise, less wear on the wire, and at less expense. In switching operations, the use of a trolley wheel is better rather than a sliding contact shoe for the reason that such a shoe, when backing up through switches, is likely to become entangled with and damage the overhead wires and appurtenances. My removable shoe is superior to the ordinary shoe fixed on a trolley pole as in case of accidental damage to the shoe, it may be quickly removed and another inserted, or the trolley wheel used instead.

The above objects have been accomplished by the means which are hereinafter described and claimed, and which are illustrated in the accompanying drawings, in which Fig. 1 is a side elevation of my improved shoe as releasably mounted and secured upon a trolley-wheel, and Fig. 2 is a front elevation of the same. Fig. 3 is a detail side elevation of said shoe and its fastening means as removed from the trolley-wheel; Fig. 4 is a cross-section of a trolley-wire, said shoe, and the tread portion of a trolley-wheel, as operatively assembled together, and Fig. 5 is an elevation of one end of the shoe-body showing the T-head thereon.

Similar numerals of reference denote cor-

responding parts throughout the several views.

The trolley-wheel 2 is rotatably mounted between the terminal forks of a trolley-head 8 on a trolley-pole 11.

The numeral 1 denotes a trolley-shoe of semi-circular or arcuate contour whose upper edge is longitudinally concaved or troughed for sliding electrical contact with and to prevent its lateral displacements from an elevated trolley-wire 3. The under or concave edge of said shoe is made triangular in cross section to fit in electrical contact the V-shaped circumferential groove of the trolley-wheel 2.

The forward depending end of the shoe 1 is diminished and supplied with a T-head 4. In a cross web of the bifurcation of the trolley-head 8 is located a slot 5 elongated longitudinally therewith and opening into the interspace of the bifurcations. The trolley-shoe 1 may be secured to the trolley-head 8 by first placing it at an angle therewith to permit the T-head 4 to traverse the slot 5, and then the shoe is turned ninety degrees causing the T-head to become interlocked with the trolley-head 8, the shoe 1 then being swung over to engage the circumferential groove of the trolley-wheel 2. The opposite end of the shoe 1 has a transverse hole to receive an end-link of a short chain 7 which has a terminal hook 6, the latter having the usual movable tongue whereby it may be interlinked with a ring 9 loosely mounted in an orificed integral ear 10 projecting from the lower face of the trolley-head 8. It will be seen that said engaging means for and the chain-connection 7-6 secures the shoe removably upon the trolley-wheel although somewhat loosely and not rigidly, as it is desirable that a little relative play be permitted so that the shoe may adjust itself for backing-up movements or otherwise without breakage.

The shoe is easily removed for replacement, or to permit alternative use of the trolley-wheel.

Having described my invention, what I claim as new and desire to secure by Letters Patent, is:

1. A conducting shoe for electrical sliding contact with an electrical conductor, and a trolley-wheel upon which said shoe is removably mounted.

2. A conducting shoe for electrical sliding contact with an electrical conductor, a trolley-wheel in electrically conducting contact with said shoe, and means for securing said shoe removably upon said trolley-wheel.
3. A conducting shoe for electrical sliding contact with an electrical conductor and having one end formed with engaging-means, a trolley-head having engaging-means adapted to releasably interlock with the engaging-means on said shoe, and a trolley-wheel mounted upon said trolley-head, said shoe being loosely seated upon and engaging the groove in said wheel.
4. In combination, a trolley-head, a trolley-wheel mounted thereon, a sliding-contact shoe seated upon said wheel and having one end formed at one end with a T-head, said trolley-head having an elongated slot to receive said T-head and interlock detachably therewith, and also having an orificed ear, and flexible connecting-means separably connected between the opposite end of said shoe and said ear to clamp the shoe removably upon said trolley-wheel.

Signed at Waterloo, Iowa, this 9th day of April, 1921.

WILLIAM G. LAMB.
